UNITED STATES PATENT OFFICE

ELMER J. GROSS, OF CHICAGO, ILLINOIS, ASSIGNOR TO CHICAGO GYMNASIUM EQUIPMENT COMPANY, OF CHICAGO, ILLINOIS, A CORPORATION OF ILLINOIS

BASKET-BALL BACKBOARD

Application filed January 25, 1928. Serial No. 249,342.

This invention relates to backboards for use in basket-ball games and the like. The main purpose of the invention is to provide a board which is light and durable, and has the desirable characteristics of wood boards, but still is not subject to warping or cracking, and which presents a perfectly plain and hard surface. In this respect the improved board is not inferior to glass boards but 10 avoids the weight and fragile characteristics of boards of that class.

A further object of the invention is to provide a basket-ball back-board having a core of softer, lighter and more resilient material than its surface material or casing, and thus to combine the desirable qualities of resilience and lightness with a good wearing surface.

An illustrative embodiment of this invention is shown in the accompanying drawings in which:

Figure 1 is a perspective view of a basket-ball goal, showing the wall, the backboard mounted on the wall, and the basket mounted 25 on the board in the manner required by the rules of the game of basket-ball.

Fig. 2 is a detailed perspective view illustrating the construction of the backboard.

Fig. 3 is a fragmental elevation of the rear 30 of the board, with portions broken away and parts shown in section.

The invention may be carried out by the use of manufactured boards wherein a fibrous core is sheathed in metal. The core is preferably formed of a plurality of veneer sheets and is covered with a non-corrosive metallic casing, all compactly pressed together.

Referring to the drawings, the backboard 1 consists of a wooden laminated body portion 2 which is covered by a sheet metal casing consisting of a sheet 3 which is glued to the back of the body portion, and the sheet 4 which is glued to the face of the body portion 2.

The sheet 4 is bent around the edges of 45 the body portion 2, and is provided with inwardly projecting flanges 5 which lap over the edges of the back sheet 3; and the sheets are preferably soldered together at the edges so that moisture cannot penetrate into the 50 interior of the board.

Suitable cleats 6, 7 and 8 are fastened to the back of the board by means of the wood-screws 7, or any other suitable fastening means. The supporting posts 8 are mounted on the back of the board 1, and are secured to the supporting wall 10 by means of the flange plates 11 which are threaded on the inner ends of the post 8.

The basket 12 is mounted by means of a clip 13, to the face of the board.

The backboard of this invention is light in construction and can be easily mounted so that it is firmly held in position; and the board has the proper resiliency characteristics to cause the ball to rebound accurately. All of the boards are substantially alike, and of uniform characteristics, so that the players do not have to make allowances for any special board. The metal covering prevents the board from absorbing moisture and becoming warped and deformed; and provides a smooth hard surface which is backed up by the resilient laminated wooden body with which the covering is held in close contact by gluing.

I claim:

1. In a basket-ball backboard, a laminated wood body portion, and a sheet metal covering glued to the face of the body portion.
2. A basket-ball backboard consisting of a laminated wood body portion and a sheet metal casing covering the body portion and glued to the forward surface thereof substantially throughout its entire area.
3. In a basket-ball backboard, a laminated wood body, a metal sheet glued to the back of the body, and a metal sheet glued to the front surface of the body throughout its entire area and bent down around the edges of the body and flanged inwardly to lap over the edges of said back sheet, the sheets being soldered together to form a moisture proof covering for the body.
4. Basket-ball backboard, comprising a metal casing, and a fibrous filler in the casing secured substantially throughout its entire front surface to the inner surface of the forward side of the casing rendering the rebound conditions of the backboard similar to the rebound conditions of the filler.

5. Basket-ball backboard, comprising a metal casing having soldered seams for excluding moisture, a filler comprising laminated fibrous material in the casing, and means between the filler and casing rigidly 5 securing substantially all portions of the forward side of the latter to the filler, for imparting the rebounding characteristics of the filler to the forward side of the casing.

10. A basket ball back-board consisting of a laminated wood body portion composed of sheets of veneer, and a sheet metal casing comprising a metal sheet glued to the back of the body portion, and a metal sheet glued to the front surface of the body portion, the 15 sheets of veneer and the metal sheets being arranged in parallel planes and all tightly and compactly pressed together, the edges of the front sheet of metal being bent around the edges of the body portion and extended inwardly to form projecting flanges overlapping the back sheet and secured to the same to form a moisture-proof covering for the body portion.

20. Signed at Chicago this 23d day of January,
25 1928.
